UNITED STATES PATENT OFFICE

LEWIS D. HARNETT, OF COLUMBUS, OHIO, ASSIGNOR TO THE BUCKEYE BLOWER COMPANY, OF COLUMBUS, OHIO, A CORPORATION OF OHIO

DOUBLE RADIATOR WITH MEANS OF EXPANSION ON RADIATORS

Application filed August 15, 1931. Serial No. 557,218.

My invention relates to heating and ventilating apparatus.

It is the object of my invention to provide a novel form of radiation comprising two radiators having a common header at one end and independent headers at the other, preferably so arranged that one header will slide upon the other, and independent control valves for the respective radiators.

10 It is a further object of my invention to provide means on said radiators for guiding air thereover, first over one radiator and thence over the other radiator forming continuous, transverse air passageways irrespective of the independent movement of the radiators and their guiding means due to different rates of expansion and contraction of the sections of the radiator which may be subject to different temperatures at the same time.

Referring to the drawings:

Figure 1 is a front elevation of the heating and ventilating unit, partially in section, with the cover partly removed from the front 25 of the radiator and with one of the fan casings partly broken away to show the arrangement of the fan;

Figure 2 is a section on the line 2—2 of Figure 1;

30 Figure 3 is a perspective of the radiator with the header partially broken away showing the common header for the two radiators;

Figure 4 is a similar view showing the arrangement of the independent headers which 35 are arranged to slide one on the other.

Referring to the drawings in detail, 1 indicates the front of a casing having the bottom 2, a recirculation grill 3 in the front 1 and side walls 4 and 5. These side walls have 40 interiorly disposed brackets 6 and 7 for supporting the radiators.

The back of the casing 8 is provided with the fresh air inlet opening 9 controlled by the damper 10. Air passes upwardly through 45 the fan 11 in the casing 12 and discharges through the opening 13 into the chamber 14 and thence passes over the radiators 15 and 16 out the air exit opening 17 in the top 18.

50 Each of these radiators is provided with a plurality of transversely-arranged vertical

plates 19 having turned-over, angular, U-shaped ends 20 abutting against one another to form vertical air passageways 21 through which air flows over the pipes 22 and 23 respectively of the radiators 15 and 16.

These passageways are substantially in line with one another although the vertical plates 21 are not continuous but independent sets of these plates are mounted on each set of the pipes 22 and 23. These pipes are mounted at one of their ends in a common header 24 having independent steam chambers 25 and 26 supplied by the pipes 27 and 28. The header is divided by a partition 29 to form the steam chambers 25 and 26. Independently controlled valves 30 and 31 control the pipes 27 and 28. Independent exit pipes 32 and 33 are provided for connection to the independent headers 34 and 35. The top header 34 is adapted to slide upon the bottom header and the bottom header is mounted upon a leg 36 which enables it to slide as it expands and contracts upon the bracket 7 on the inside of the casing.

Referring to the passage of the air through the system, the fresh air enters through the opening 9, passes upwardly under the influence of the fan 11, discharges through the opening 13 and into the expansion chamber 14 and thence over the radiator pipes 22 and 23 between the plates 19 through the passageways 21 and out the outlet opening 17.

In operation, as the steam is independently cut on and off in the two radiators the pipes 22 and 23 expand and contract independently depending upon their temperature.

Heretofore, this has resulted, when the pipes were mounted in common headers, in a loosening of the pipes in the headers making it difficult to keep tight steam connections. Furthermore, it has been difficult to employ independent controls because of this result.

On the other hand, independent radiators 95 not connected into a common header make it difficult to provide proper alignment and support. By arranging the radiators with a common header at one end and supporting headers slidably mounted, a single support 100

at either end is sufficient for supporting the entire radiator system.

The fans 11 are operated by the motor 11a from the armature shaft 11b. The damper 10 may be controlled either automatically or by hand through the button 37.

It will be understood that I desire to comprehend within my invention such modifications as may be necessary to adapt it to varying conditions and uses.

Having thus fully described my invention, what I claim as new and desire to secure by Letters Patent, is:

1. In combination, in a radiator, of a common header having separate supply chambers, radiator pipes connected to said chambers, independent radiating fins mounted on said pipes forming with one another passageways.

2. In combination, in a radiator, of a common header having separate supply chambers, radiator pipes connected to said chambers, independent radiating fins mounted on said pipes forming with one another passageways, said fins and passageways being so arranged that they are in substantial alignment for continuous passage of air therethrough irrespective of the independent movement of said pipes.

3. In combination, in a radiator, of a common header having separate supply chambers, a set of radiator pipes connected to each chamber, radiating fins mounted on each set of said pipes having passageways therebetween, and independent headers at the other ends of said pipes.

4. In combination, in a radiator, of a common header having separate supply chambers, a set of radiator pipes connected to each chamber, radiating fins mounted on each of said pipes having passageways therebetween, said fins and passageways being so arranged that they are in substantial alignment for continuous passage of air therethrough irrespective of the independent movement of said pipes, and independent headers at the other ends of said pipes.

5. In combination, in a radiator, of a common header having separate supply chambers, a set of radiator pipes connected to each chamber, radiating fins mounted on each set of said pipes having passageways therebetween, and independent headers at the other ends of said pipes slidably engaging one another.

6. In combination, in a radiator, of a common header having separate supply chambers, a set of radiator pipes connected to each chamber, radiating fins mounted on each set of said pipes having passageways therebetween, said fins and passageways being so arranged that they are in substantial alignment for continuous passage of air therethrough irrespective of the independent movement of said pipes, and independent

headers at the other ends of said pipes slidably engaging one another.

7. In a heating and ventilating unit, a casing having an air inlet opening at the bottom and an air outlet opening at the top, dual radiators mounted therein therebetween, a common header supported on said casing for said dual radiators at one end thereof, and independent headers for said radiators supported on said casing in the other end thereof.

8. In a heating and ventilating unit, a casing having an air inlet opening at the bottom and an air outlet opening at the top, dual radiators mounted therein therebetween, a common header supported on said casing for said dual radiators at one end thereof, and independent headers for said radiators supported on said casing in the other end thereof, said independent headers being slidably mounted one upon the other and having a common support.

9. In combination, in a heating and ventilating unit, of a casing, a fan, an air inlet and an air outlet opening, a plurality of radiators, each having an independent set of radiating fins comprising vertically-disposed air chambers in alignment with one another in the direction of the passage of air through said openings actuated by said fan, a common header for said radiators at one end and independent headers at the other.

10. In combination, in a heating and ventilating unit, of a casing, a fan, an air inlet and an air outlet opening, a plurality of radiators, each having an independent set of radiating fins comprising vertically-disposed air chambers in alignment with one another in the direction of the passage of air through said openings actuated by said fan, a common header for said radiators at one end and independent headers at the other, and means for supporting said common header at one end on the casing without movement, and means for supporting said independent headers on the casing at the other end of the radiators whereby one of said independent headers is supported without movement and the other is slidably mounted thereon.

11. A new article of manufacture for use as a radiator comprising a common header having separate chambers at one end, radiator pipes connected thereto and independent headers at the other end, and separate sets of transverse fins on each pipe forming with one another substantially continuous air passageways over both pipes while permitting independent movement of each pipe with its own set of transverse fins.

12. A new article of manufacture for use as a radiator comprising a common header having separate chambers at one end, radiator pipes connected thereto, independent headers at the other end, said independent headers resting slidably one on the other, and

separate sets of transverse fins on each pipe forming with one another substantially continuous air passageways over both pipes while permitting independent movement of each

5 pipe with its own set of transverse fins.

13. A new article of manufacture for use as a radiator comprising a common header having separate chambers at one end, radiator pipes connected thereto, independent

10 headers at the other end, said independent headers resting slidably one on the other, a common means for supporting said respective

headers, and separate sets of transverse fins on each pipe forming with one another sub-

15 substantially continuous air passageways over both pipes while permitting independent movement of each pipe with its own set of transverse fins.

20 In testimony whereof, I affix my signature.
